TOBACCO PIPE

William Raymond Faifer and Theodore R.
Harvey, Vinita, Okla.

Application October 26, 1931. Serial No. 571,234

2 Claims. (Cl. 131—12)

This invention relates to tobacco pipes, and more particularly to tobacco pipes embodying a unique construction to provide for carrying a pipe cleaner in the pipe at all times.

5 One object of the invention is to provide a tobacco pipe of simple construction, inexpensive to manufacture, and capable of long efficient service.

10 Another object of the invention is to provide a tobacco pipe of unique construction embodying means for carrying a pipe cleaner with the pipe at all times, the pipe cleaner being concealed from view and in a position in the pipe to permit of its ready removal therefrom and quick insertion into the smoke passage to clean the same.

15 With the above and other objects in view, the invention consists in the construction and novel combination and arrangement of parts herein-after described, illustrated in the accompanying drawing, and set forth in the claims hereto appended, it being understood that various changes in the form, proportion, and minor details of construction, within the scope of the claims, may be resorted to without departing from the spirit of the invention or sacrificing any of the advantages thereof.

The invention will be more readily understood by reference to the accompanying drawing, in which,

20 Figure 1 is a top plan view of a tobacco pipe embodying the present invention.

Fig. 2 is a vertical sectional view on the line 2—2 of Fig. 1, taken in the direction of the arrows.

25 Fig. 3 is a side elevation, partly in section, on the lines 3—3 of Fig. 1.

Fig. 4 is a cross sectional view on the line 4—4 of Fig. 3.

Fig. 5 is a top plan view, partly in section, showing a slight modification.

30 Fig. 6 is a side elevation, partly in section, showing the present invention applied to a curved stem pipe.

Fig. 7 is a plan view of the mouth piece of the pipe shown in Fig. 6.

35 Referring more particularly to the drawing, in which like reference characters indicate like parts, the numeral 1 indicates the usual bowl portion of a pipe, having integral therewith and extending therefrom a stem portion 2. The stem portion 2 is provided with a recess 3 which is shown of oval formation, but it may be of any desired shape to receive the projection 4 of the outer portion of the stem 5. This projection 4 is of course to be of the same shape or configuration as the recess 3.

The outer end of the stem 5 is provided with the usual tip 6, and a portion of the outer end 6 forms the mouthpiece. The usual smoke passage 7 connects with the interior 8 of the bowl, as at 9. This passage extends throughout the length of the stem portion 2 and the stem portion 5 and terminates in an opening 10 at the tip 6. The tip of the mouthpiece 6 may, if desired, be provided with a recess 10a.

40 A cleaner receiving opening 11 extends from the outermost extremity of the bowl portion, at 11', through the base part 12 of the bowl portion and through the stem portion 2, and into the stem portion 5, and terminates short of the tip of the mouthpiece, as at 13. The recess 10a is in effect 45 a short bore or "dummy passageway" that is substantially in alignment with the closed end portion adjacent thereto of the cleaner receiving opening 11. The smoke passageway 7 and the dummy passageway 10a afford a symmetry in 50 appearance as to the external tip or outer end portion of the mouthpiece. The mouthpiece having the smoke passageway and the dummy passageway arranged as described also results in a construction that is readily convertible into a 55 mouthpiece of the style shown in Fig. 5. This conversion being readily accomplished merely 60 by a workman inserting a drill of the proper size into and through the dummy passageway 10a and drilling out the partitioning material at 13 65 which separates the dummy passageway 10a on 70 the one hand from the closed end portion of the cleaner receiving opening 11 on the other hand. A pipe cleaner 14, which is preferably of flexible 75 material in the form of a wire or the like, is 80 adapted to be inserted into the opening 11 and is 85 removably carried therein. The pipe cleaner 14 is provided with a head or projection 15 at 90 its outer end which permits the cleaner to be 95 readily and quickly removed from the opening 11 and inserted into the smoke passage 7 to clean the same in the event this passage has become clogged with tobacco, nicotine, or saliva.

95 Fig. 5 shows a slightly modified form of our invention, which consists in having the cleaner receiving opening extending from the tip of the mouthpiece entirely through the stem portions 100 of the pipe into the base 12 of the bowl portion and terminating short of the end of the bowl portion, as at 13.

105 In Fig. 6 the invention has been shown as embodied in a curved stem pipe. It will be understood that in the curved stem pipes the pipe cleaner might well extend from the tip portion of the mouthpiece, shown in Fig. 5, through the 110

stem portions of the pipe and into the base of the bowl.

The cleaner receiving opening 11 is separate from and unconnected with the smoke passage 7, 5 and the interior of the bowl 8. This permits the pipe cleaner 14 to be carried or stored in the cleaner receiving opening 11 and allows of the usual smoking of the pipe, that is, the smoke will be confined entirely to the smoke passage 7, 10 which is in no way connected with the cleaner receiving opening 11. The cleaner receiving opening 11 is of such length as to receive a pipe cleaner 14 sufficiently long to extend from the tip 6 to the interior 8 of the bowl portion when 15 it is inserted in the smoke passage, and thereby remove all obstructions throughout the entire length of the smoke passage.

From the foregoing it will be readily seen that we have perfected a pipe construction which permits the carrying of a pipe cleaner within the pipe structure and concealed from view. The pipe cleaner is easily and quickly removable from the cleaner opening, and has a snug fit therein, which will prevent accidental displacement of 20 the cleaner.

What is claimed is:

1. A mouthpiece for a pipe comprising a member shaped at the tip or outer end thereof for reception into the mouth and at the inner end 30 for attachment to the bowl section of a pipe, which mouthpiece has a smoke passageway extending therethrough from the inner end to the tip end, a cleaner receiving opening spaced from the smoke passageway by a suitable partition,

which cleaner receiving opening extends from the inner end of the mouthpiece and terminates in a closed end near the tip end of the mouthpiece, said mouthpiece having a dummy opening 80 extending from the tip end of the mouthpiece and terminating in a closed end spaced from but near to the closed end of the cleaner receiving opening, said dummy opening or dummy passageway being in substantial alignment with the closed end of the cleaner receiving opening.

2. A tobacco pipe comprising a bowl with an integral stem and a detachable mouthpiece and provided with the usual smoke passageway extending from the interior of the bowl through the integral stem and through the mouthpiece and with a cleaner receiving opening spaced from but out of communication with the bowl receiving opening and said smoke passageway, which cleaner receiving opening is of length greater than that of the smoke passageway as provided in said integral stem and said detachable mouthpiece, said cleaner receiving opening having a closed end provided near the tip end of the mouthpiece, said tip mouthpiece having a dummy opening or passageway leading from the tip end thereof 100 towards the cleaner receiving opening and arranged in substantial alignment with the cleaner receiving opening, said dummy passageway and the tip end of the smoke passageway being arranged so as to effect a symmetrical appearance 105 at and for the extreme tip end of the mouthpiece.
